DEVICE FOR THE INTERRUPTION OF THE
FUEL SUPPLY TO A BURNER FOR LIQUID
FUEL

Adriaan Marius Isaac Hoogendam, Delft, Netherlands, assignor to Shell Development Company, San Francisco, Calif., a corporation of Delaware

Application January 11, 1937, Serial No. 119,981
In the Netherlands January 18, 1936

2 Claims. (Cl. 158—36.6)

The invention relates to a device for the interruption of the fuel supply to a burner for liquid fuel which is fed from a reservoir in which a constant liquid level is maintained. Known burners of this type are those in which the fuel is gasified in an annular groove filled with absorbent material, whilst the combustion of the gases takes place between two cylindrical or conical jackets provided with air supply openings. Such burners are commonly known as "range" burners.

The invention has for its object a device requiring but a very small regulating power for shutting-off and opening again the fuel supply and nevertheless ensuring an absolutely reliable shut-off.

Where the magnitude of the regulating power required does not play a part, as with hand-operated devices, a cock or needle valve may be applied as a shutting-off member, but in those cases where the operation is automatic, the direct regulating power available is usually insufficient to obtain an efficient shut-off with such valve members. This problem presents itself, for instance, in cases where the burner is used for heating a hot water reservoir, and has to be extinguished automatically as soon as the water has reached a certain temperature. The sufficiently sensitive thermostats usually applied for this purpose develop but a small direct regulating power.

According to the invention, a weir is fitted in the line between the feed reservoir and the burner, which, with a view to interrupting the supply, can be raised above the liquid level. No difficulties are encountered in constructing the weir in such a manner that only little power is required for raising it, which power can readily be supplied by a thermostat. Once the weir has been raised to above the constant liquid level, it is absolutely impossible for any further liquid to reach the burner over the weir.

Various embodiments of the device according to the invention are possible. For instance, the weir may be connected rigidly to the line and the latter made vertically movable at the place of the weir, or the weir may form a vertically movable cup fitted in an open reservoir forming part of the feed line.

The drawing shows an example of each of these two embodiments. Fig. I is a plan view showing a preferred form of shut-off mechanism. Fig. II is an elevation partly in section of the matter shown in Fig. I. Fig. III is an enlarged side elevation of the weir of Fig. I and Fig. II. Fig. IV

is an elevation of an oil feed tank showing another form of weir.

Referring to Figures I and II, 1 is a fuel tank in the form of a Mariotte bottle from which through an opening at the bottom thereof the feed reservoir 2 is always kept filled with fuel to a constant level.

Through the piping system, 3, 4, 5, 6, 7, and 8, this fuel is fed to the burner 9.

Within this system, the section 5, 6 and 7 can turn about a horizontal axis. For this purpose, the piping parts 4 and 8 are of flexible construction. The parts 5 and 7 unite at 6, where the line has an opening at the top and forms at the bottom an edge or weir 10 (see Fig. III) which is preferably as sharp as possible. While the burner is operating, this weir 10 lies below the constant liquid level, so that the fuel, as shown in Fig. III flows over it. For discontinuing the supply of fuel to the burner, it is only necessary to turn the section 5, 6, 7 about the axis until the weir is raised above the constant liquid level. Since this requires but little power, it can readily be effected by means of a thermostat 11 attached to the parts 5 and 7. The heat sensitive bulb 12 of the thermostat may, for instance, be fitted in the water space of a hot water geyser heated by the burner 9. The opening at 6 is necessary in order to avoid siphoning of fuel over the weir 10 after this has been raised to above the constant level.

A branch 13 of the line 3 leads to a continuously burning pilot 14 which serves to reignite the extinguished burner 9 as soon as the fuel supply is reopened.

With the embodiment illustrated in Fig. IV, the fuel piping itself is immovable, but a vertically movable cup with weir is provided in a reservoir fitted in the line. In Fig. IV, 1 is also the Mariotte bottle positioned over a fuel feed reservoir 15 filled from it. This feed reservoir 15 is surrounded by a second reservoir 16 connected to the burner by means of the line 3. Between the walls of the two reservoirs a cup 17 is provided which can turn about a horizontal axis at 18 and into which the fuel from reservoir 15 can pass through opening 19. At the side opposite the axis 18, the cup has an opening 20 about at the height of the liquid level, the lower edge of which serves as a weir for the fuel.

In the position shown in the drawing, this opening 20 lies below the liquid level; however, when the cup is raised by means of the extension 21, the opening may come to lie above this level, so that the supply of fuel to the burner through the 55

line 3 is interrupted. The movement of the cup may also in this case be derived from a thermostat 11.

The fuel supply interrupting device, according 5 to the invention, may also quite suitably be operated electrically, e. g., by means of an electromagnet operated by a thermostat which is of particular advantage in cases where the distance between the temperature-sensitive element and the shutting-off member is considerable. Such a 10 condition might occur where a burner used for heating a room is operated by a room thermostat.

I claim as my invention:

1. A device for the interruption of the fuel supply to a burner for liquid fuel fed from a reservoir in which a constant liquid level is maintained comprising a reservoir, a cup in said reser- 15

voir, said cup having an opening in its vertical wall, a hinge connecting one side of said cup to the reservoir, an elongated handle attached to the opposite side of said cup, a thermostat connected to said handle whereby said cup may be raised 5 above the liquid level in said reservoir.

2. A device for the interruption of a fuel supply to a burner for liquid fuel fed from a reservoir in which a constant liquid level is maintained comprising: a reservoir, a cup in said reservoir, 10 said cup having an opening in its vertical wall, a hinge connecting one side of said cup to the reservoir, and an elongated handle attached to the opposite side of said cup whereby said cup may be raised above the liquid level in said reservoir. 15
